UNITED STATES PATENT OFFICE.

STILLWELL R. HARCOURT, OF CHICAGO, ILLINOIS, AND OSCAR H. ANDERSON, OF GRAND HAVEN, MICHIGAN, ASSIGNEES TO STORY & CLARK PIANO CO., OF GRAND HAVEN, MICHIGAN, A CORPORATION OF ILLINOIS.

MECHANISM FOR REGULATING THE EXPRESSION IN APPARATUS FOR PLAYING MUSICAL INSTRUMENTS.

Application filed January 25, 1924. Serial No. 688,404.

To all whom it may concern:

Be it known that we, STILLWELL R. HARCOURT and OSCAR H. ANDERSON, citizens of the United States, residing at Chicago, in the county of Cook and State of Illinois, and Grand Haven, in the county of Ottawa and State of Michigan, respectively, have invented a new and useful Improvement in Mechanism for Regulating the Expression in Apparatus for Playing Musical Instruments, of which the following is a specification.

This invention relates to improvements in apparatus for playing musical instruments and more especially to that kind of apparatus such as player pianos, wherein the note-striking mechanism is actuated by striker-pneumatics controlled by a perforated note-sheet passing over the tracker-board.

This invention more especially relates to the expression means of such devices. One of the objects of the invention is to provide such devices with means, whereby the notes of the musical instrument may be struck with varying degrees of intensity, in order to give more accurate or artistic expression. Such expression means is adapted to be controlled by supplemental expression holes in the tracker-board in connection with supplemental expression perforations or apertures in the music sheet, adapted to register therewith.

In that form of device embodying the features of my invention shown in the accompanying drawings, Fig. 1 is a view in front elevation showing somewhat diagrammatically the different parts of my invention as the same are embodied in a player piano, Fig. 2 is a view taken as indicated by the line 2 of Fig. 1, Fig. 3 is a view taken as indicated by the line 3 of Fig. 2, Fig. 4 is a view taken as indicated by the line 4 of Fig. 1, Fig. 5 is a view taken as indicated by the line 5 of Fig. 4, Fig. 6 is a view taken as indicated by the line 6 of Fig. 4, Fig. 7 is a view taken as indicated by the line 7 of Fig. 8, Fig. 8 is a view taken as indicated by the line 8 of Fig. 7, Fig. 9 is a view taken as indicated by the line 9 of Fig. 8, Fig. 10 is a view taken as indicated by the line 10 of Fig. 7, Fig. 11 is a view taken as indi-

cated by the line 11 of Fig. 7, Fig. 12 is a view taken as indicated by the line 12 of Fig. 10, Fig. 13 is a vertical sectional view of the switch for shutting off the crest valves and Fig. 14 is a vertical sectional view of a striker-pneumatic.

In Fig. 1 there is shown, in general, and somewhat diagrammatically, the parts of my invention illustrating one manner in which they may be used in connection with apparatus for playing musical instruments. It is to be understood, however, that this showing is merely for the purpose of giving an example of one use of the invention. The invention is not to be restricted to this particular arrangement or use, it being within the spirit and scope of the invention to use the expression regulating mechanism and parts thereof in connection with other forms and types of apparatus for playing musical instruments.

As shown in the drawings, 20 indicates a compartment, sometimes termed wind-chest, from which air is partially exhausted by any suitable pumping means (not shown) through the pipe 21, to maintain within the wind-chest 20 a partial vacuum. Connected to the wind-chest 20 by means of 75 the connection 215 is a bellows 22 acting as a governor and operating to maintain the degree of vacuum in the wind-chest 20 constant, except as said governor is affected by bleeds to be hereinafter explained more in detail. The governor 22 itself is not shown in detail since such governors comprising, in general, a spring controlled bellows, are in common use. The vacuum from the wind-chest 20 is communicated by the pipe 80 23 to one end of the stack 24 which extends the entire length of the keyboard and has connected to it the striker-pneumatics controlling the particular notes. The terminology of the different parts of a player piano of this type is more or less arbitrary and the terms are differently used by different persons. Frequently the passage 24 extending the length of the keyboard into which the striker-pneumatics open, is referred to as a 90 wind-chest and the pipes 23 connecting the wind-chest to the exhausting mechanism, as stacks. We prefer, however, to call the compartment 20 which is connected directly 95 100

to the exhausting pump as the wind-chest and apply the term stack to the compartment 24 into which the striker-pneumatics open. We believe this use of terms to be 5 the better practice. The keyboard of instruments of this kind is ordinarily divided in two parts substantially at the center so that the expression of one-half of the notes may be regulated independently of the 10 other notes. When the keyboard is so divided, there is a separate set of expression regulating devices for each side of the keyboard. In illustrating the present invention, we assume that the keyboard is so 15 divided and show in detail but one side, it being understood that the apparatus is duplicated for regulating the expression of notes on the other side. It is obvious also that if desired, the keyboard could be divided into more than two parts, and each 20 part have a separate expression regulating apparatus. When the board is divided into two parts with two corresponding sets of expression regulating apparatus, it is customary 25 to place the respective groups of apertures in the tracker-board controlling such expression regulating apparatus at the two ends of the tracker-board. In the present case, since we have shown but one expression 30 regulating apparatus, we are also showing but one end of the tracker-board with the apertures therein for controlling such expression regulating apparatus. In the present case, we have shown four of 35 such apertures operating in connection with our expression regulating apparatus and a fifth aperture controlling movement of the hammer rail. There are now on the market note sheets having at each end five series 40 of holes for controlling expression and our apparatus is so designed that it can be used in connection with such note sheets, now on the market. The fifth hole referred to above is at the extreme end of the tracker-board and forms no part of the present 45 invention.

A indicates, in general, a crest valve controlling the passage between the wind-chest 20 and the pipe 23 which leads to one end 50 of the stack 24. It is to be understood, as stated above, that there is a duplicate of this crest valve together with the other parts of our invention on the other side of the piano. The pipe 23 opens into one end of the stack 55 24 (see Fig. 14) and since the stack 24 is divided at the center each of the pipes 23 controls substantially half of the notes on the instrument.

B indicates, in general, a bleed box having 60 three bleeds adapted to bleed air through the pipe 25 into the governor 22 in order to decrease the vacuum therein and consequently decrease the vacuum in the wind-chest 20, pipe 23 and stack 24. Such 65 decreasing of the vacuum in the stack 24

will obviously operate to decrease the intensity with which the striker-pneumatics communicating therewith operate. It is believed that the ordinary construction of 70 striker-pneumatics and their communication with the stack is well known; but for the purpose of additional clarity there is illustrated in Fig. 14 one striker-pneumatic 26 showing its connection by the port 27 with the stack 24. 28 indicates the rod connected to the hammer (not shown). A valve 29 of the ordinary form controls communication between the stack 24 and the striker-pneumatic 26. This valve 29 is provided with a stem 30 the end of which bears 80 against a diaphragm 31 which covers the end of the opening 32 which terminates at its other end with a note aperture 33 in the tracker-board 34. The operation of these parts, we believe, is well known. When the note aperture 33 is uncovered by a perforation in the note sheet, atmospheric air is admitted behind the diaphragm 31 causing it to move to the right (as viewed in Fig. 14) to move the valve 29 to the right. This movement of the valve 29 to the right closes 90 the hole 35 opening into the atmosphere and at the same time permits the vacuum in the stack 24 to be communicated through the port 27 into the pneumatic 26 to collapse 95 the pneumatic, to raise the rod 28, to cause the hammer to strike the string.

C indicates, in general, a bleed control box operating in connection with the four apertures 35, 36, 37 and 38 at the end of 100 the tracker-board for controlling the bleeds in the bleed box. There are three bleeds in the bleed box and four expression holes (not counting the hole controlling the hammer rail which will not be further considered in 105 this specification) at the end of the tracker-board. Aperture 35 does not open any of the bleeds. Aperture 36 opens the smallest bleed, aperture 37 the intermediate and aperture 38 the largest bleed of the three. The bleed control box C, however, when any one of the four apertures 35, 36, 37 or 38, 110 is open, also operates a crest control box D to open the crest valve A. If desired, there may be only one crest control box operated by one bleed control box but controlling both crest valves. We have here shown the apparatus so arranged but are showing only one crest valve. When we describe the apparatus more in detail it will be seen that another pipe leads from the crest control box to the other crest valve (not shown).

Attached to the lower end of the crest control box D is a rewind control box E. This rewind control box operates the shut-off pouches at the ends of the pipes 23 where they join the wind-chest 20. Obviously, 120 there are two of such shut-off pouches, one for each of the pipes 23; but only one will 125

be shown and described in detail. When this is done and the rewind control box E is described more in detail, it will be seen that another pipe leads from this box E to 5 the other shut-off pouch (not shown).

F indicates a bleed shut-off control box operating to shut off all the bleeds during the rewinding operation so that as the note sheet is rewound, there will be no bleeding 10 of air as the expression holes in the note sheet pass backwardly over the expression apertures in the tracker-board.

We will first describe the crest valve A. 40 indicates a port between the wind-chest 20 and the chamber 41 into which the end of the pipe 23 opens. Arranged adjacent the port 40 is a bellows 42. It will be seen that when this bellows 42 is expanded, the port 40 will be closed and when the bellows 20 42 is collapsed the port 40 will be opened. It is obvious, therefore, that the rate of withdrawal of air through the port 40 may be varied by movement of the bellows 42. Opening into the bellows 42 is a pipe 43 25 leading to the crest control box D. The pipe 44 leads from the other crest valve (not shown) to the crest control box D. The crest control box D has two valves in connection with the two crest valves respectively, and since they are the same, we will describe but one in detail. Details of the crest control box D are shown in Figs. 4, 30 5 and 6. Formed within the box D is a chamber 45 communicating by means of the port 46, with the manifold 47 which in turn is connected by the tube 48 with the pipe 25 so that there is maintained within the compartment 45 a partial vacuum transmitted thereto from the exhausting mechanism. Adjacent the chamber 45 is a smaller 40 circular chamber 49 covered by a diaphragm 50. Above the diaphragm 50 is arranged a valve having the two valve discs 51 and 52 mounted on a valve stem 53. The lower 45 end of the valve stem 53 lies close to the diaphragm 50. The pipe 43 leading to the crest valve enters at about the center of a port 54 which leads from the chamber 45 to the atmosphere. When the valve is in 50 the position shown in Fig. 4, the disc 52 closes communication between the pipe 43 and the chamber 45 and opens it to the atmosphere. When the valve is raised the disc 51 closes communication between the pipe 43 and the atmosphere and opens it to the chamber 45 so that air is withdrawn 55 from the pipe 43. When the diaphragm 50 is raised, the valve is so moved as to open communication between the pipe 43 and the vacuum chamber 45. The valve is normally 60 in the position shown in Fig. 4 with the end of the pipe 43 open to the atmosphere so that atmospheric pressure is in the crest valve A operating to hold the bellows 42 expanded and the crest valve closed. It is 65 to be noted that as the bellows 42 expands, its upper surface approaches the port 40 and closes the opening. We speak, therefore, of the crest valve A as being closed when the bellows is expanded and open 70 when the bellows is collapsed. Besides the port 40 there is another port 55 leading from the wind-chest 20 to the chamber 41. This port is controlled by an automatic valve 56 of well known construction forming no part 75 of the present invention. The valve 56 operates to permit a more or less steady withdrawal of air from the chamber 41 through the port 55, for the normal operation of the piano. The crest valve A when open permits an extra withdrawal of air through the port 40 and a consequent increased vacuum and consequent louder striking of the notes or fortissimo effect. When the crest valve A is closed, this extra 80 withdrawal of air through the port 40 is shut off and the instrument operates in the normal manner. When atmospheric air is admitted through the pipe 43 into the bellows 42, such bellows is expanded and the crest valve closed. When atmospheric air is cut off from the pipe 43, the crest valve is opened. As has been stated, this admission of atmospheric air or cutting it off is controlled by the valve discs 51 and 52 in 85 the crest control box D. The operation is as follows. Below the diaphragm 50, there enters a pipe 57 which has a Y connection 57^a with one branch 57^b leading to a push button 57^c and so constructed that when this button is pushed the end of the pipe 57^b will be opened to the atmosphere. When 57^b is thus opened to the atmosphere, atmospheric air enters at 57 below diaphragm 50 (Fig. 4) to raise valves 51 and 52 thus connecting pipe 43 with the vacuum chamber 45 to open crest valve A. This button 57^c is arranged below the keyboard 58 and is adapted for manual operation so that at any time desired it may be pressed and the crest 90 valve opened. Another push button 59^c in a similar manner controls a pipe 59^b which leads to a similar valve in the crest control box D controlling the pipe 44 which leads to the other crest valve. Since the details 95 of operation of these parts is similar to those already described, the description will not be repeated. The other branch from the Y 57^a indicated by 57^d leads to the bleed control box C and the end of it is normally 100 closed but adapted to be opened to the atmosphere when any of the apertures 35, 36, 37 or 38 on the tracker-board is opened. The pipe 59^b has a similar Y connection 59^a 105 with one branch 59^d leading to the bleed control box C and likewise adapted to be opened to the atmosphere when any of the four expression apertures on the tracker-board is exposed. In other words, upon the opening 110 of any of the apertures 35, 36, 37 or 38, the 115

bleed control box C opens the pipes 57^d and 59^d to the atmosphere, thereby operating the two valves in the crest control box D to open both crest valves. Each of the pipes 57^b and 59^b also has a branch 57^c and 59^c leading to a block 60 mounted on the keyboard and provided with a switch-arm 61 adapted to close or open the ends of these pipes (see Fig. 13). If desired, the switch-arm 61

5 may be moved so that the ends of these pipes are permanently opened to the atmosphere, thus permanently opening both crest valves and putting them out of operation.

We will now describe the bleed control box 15 C and the bleed box B. The construction of these parts is best shown in Figs. 7 to 12 inclusive. Since there is a duplication of parts in these members clearly shown in the drawings, we will describe in detail only a sufficient number to show the operation of the devices. Within the box C is a chamber 62 communicating by the pipe 63 with a chamber 64 in the bottom of the bleed box B. The chamber 64 is connected to the pipe 25 so that there is always maintained in the chambers 64 and 62 a partial vacuum from the exhausting mechanism. Connecting with the chamber 62 by suitable ports are four small bellows 65, 66, 67 and 68. The port 30 connecting the bellows 65 with the chamber 62 is shown in Fig. 12 as indicated by 69. In Fig. 7 is shown the bellows 68 with its port 70. Each of the ports leading to the four bellows 65, 66, 67 and 68 is controlled 35 by a valve adapted by its movement to admit atmospheric air to the bellows or establish communication between the bellows and the chamber 62 so that air will be withdrawn from the bellows to collapse it. The operation 40 and construction of these valves is similar. In Fig. 12 is shown the valve in connection with the bellows 65 which comprises the two discs 71 and 72 mounted on the valve stem 73. When the valve is in the position 45 shown in Fig. 12 the port 74 leading into the chamber 62 is closed and the port 75 leading to the atmosphere is open so that atmospheric air is admitted into the bellows 65. When the valve is moved to the right 50 (as viewed in Fig. 12) the port 75 is closed and the port 74 is opened so that air is withdrawn from the port 69 by means of the vacuum in the chamber 62 so that the bellows 65 is collapsed. The valve stem 73 carrying 55 the valve discs is moved in the following manner. The end of this valve stem lies adjacent a diaphragm 76 covering a circular recess 77 into which a pipe 78 leads. The end of the pipe 78 connects with the aperture 35 in the tracker-board so that when this aperture is uncovered, atmospheric air is admitted behind the diaphragm 76 to move the valve stem 73 to close the port 75 and open the port 74. The ends of 60 the pipe 57^d and 59^d are normally covered

by a block 79 attached to a wire 80 hinged at 81, 81. The movable members of the bellows 65, 66, 67 and 68 carry arms 65^a, 66^a, 67^a and 68^a, respectively, adapted to strike the wire 80 and raise the block 79 when any 70 of the bellows is collapsed. The pipe 78 has a branch 78^a leading to a chamber 82 covered by a diaphragm 83 adapted to operate a valve stem 84 carrying a valve 85 (see Fig. 9). 86 indicates a pipe connected to the aperture 36 in the tracker-board. When the valve 85 is in the position shown in Fig. 9, communication is established between this pipe 86 and the curved pipe 87 leading to a valve 88 which is the same as the valve 71, 72. By this construction, when the aperture 36 on the tracker-board is opened to the atmosphere, atmospheric air is admitted through the pipe 86, then past the valve 85 (if it is in the position shown in Fig. 9) 85 into the pipe 87 to operate the valve 88 to collapse the bellows 66. If, however, when the aperture 36 is open, the aperture 35 is also open, then, in such case, the atmospheric air coming through the pipe 78 and 90 its branch 78^a will permit the diaphragm 83 to be moved to the right (as viewed in Fig. 9) to move the valve 85 to the right to close communication between the pipes 86 and 87 so that no atmospheric air will be 95 admitted into the pipe 87. In like manner, the other bellows 67 and 68 are operated by the pipes 89 and 90 respectively, leading to the apertures 37 and 38, respectively. I have indicated, in general, the valve controlling the bellows 67 by the reference numeral 91 and the valve controlling the bellows 68 by the reference numeral 92. Each of these valves resembles the valve 71, 72 100 which has been described more in detail 105 (see Fig. 12). The pipes leading to the diaphragms back of these valves are indicated by 93 and 94. Each of the pipes 87 and 93 also has a branch 87^a and 93^a controlling two valves 95 and 96, respectively, 110 which in turn control communication between the pipes 89 and 93 and between the pipes 90 and 94 in the same manner that the valve 85 controls communication between the pipes 86 and 87 (see Fig. 9). 115

97 indicates the port leading from the valve 91 to the bellows 67, and 98 indicates the port leading from the valve 88 to the bellows 66. Each of the three ports 70, 97 and 98 has a pipe leading to a bleed valve 120 in the bleed box B. These pipes are indicated by 99, 100 and 101, respectively. Lying above the chamber 64 are three chambers 102, 103 and 104. Each of these chambers has a port opening into the atmosphere. The port connecting the chamber 104 to the atmosphere is indicated by 105. The port connecting chamber 102 to the atmosphere is indicated by 106. The chamber 103 has a 125 similar port. Each of the ports is adapted 130

to be regulated in size by a bleed valve. The three bleed valves into the chambers 102, 103 and 104 are indicated by 107, 108 and 109, respectively. The position of these three bleed valves is adapted to be adjusted as desired by the three screws 110, 111 and 112, respectively. As here shown, the valves are adjusted so that the valve 109 will give the smallest bleed, the valve 108 an intermediate bleed, and the valve 107 the largest bleed. The three chambers 102, 103 and 104 are connected to the chamber 64 by the three pipes 113, 114 and 115, respectively. The lower end of each of the pipes 113, 114 and 115, is adapted to be opened or closed by a diaphragm or pouch. These three diaphragms or pouches are indicated by 116, 117 and 118, respectively (see Fig. 7 for pouch 116). The pipes 99, 100 and 101 lead to chambers below these pouches so that when a vacuum is created below them they are lowered to uncover the ends of the pipes 113, etc. Whenever one of these pouches is raised (as 116 is shown in Fig. 7) it covers the end of the adjacent pipe. It will be seen that when atmospheric air is admitted under any of the pouches 116, 117 or 118, the vacuum in chamber 64 will raise it to cover the corresponding pipe. If, however, there is a vacuum under the pouch, the pouch will be lowered to uncover the pipe 113 to permit a bleed through the corresponding bleed valve into the chamber 64 and consequently into the pipe 25 and governor 22. Although I have here shown these bleeds as leading into the governor 22 it is obvious that the air from the bleed may enter any part of the exhausting mechanism or air line.

It is believed that the operation of the bleeds is now clear. When the aperture 35 on the tracker-board is uncovered, atmospheric air is admitted into the pipe 78 to collapse the bellows 65. The collapse of this bellows uncovers the ends of the pipes 57^d and 59^d to open both crest valves as has been explained. It is to be noted that there is no bleed in connection with the bellows 65 and consequently all that happens when the aperture 35 is uncovered is the opening of both crest valves. When the aperture 36 is uncovered the pipe 86 is opened to the atmosphere and normally this pipe communicates with the pipe 87 so that the bellows 66 is collapsed and also the bleed 109 opened by a lowering of the pouch 118. Opening apertures 36 also opens both crest valves. Likewise the aperture 37 will open both crest valves and open the bleed 108 and the aperture 38 will open both crest valves and open the largest bleed 107. So far we have assumed that any one of the apertures 35, 36, 37 or 38 alone is opened. There is also an interlocking mechanism which will prevent the bellows 66 from collapsing if the bellows 65 is already collapsed and likewise the bellows 67 from collapsing if the bellows 66 is already collapsed and likewise the bellows 68 from collapsing if the bellows 67 is already collapsed. This interlocking mechanism includes the valves 85, 95 and 96 which have already been described. In other words, if atmospheric air is admitted in the pipe 78, the valve 85 is closed so that if the aperture 36 is opened, there will be no effect on the bellows 66 or the bleed 109 because the valve 85 is closing communication between the pipes 86 and 87. Likewise if the aperture 36 is open and the bellows 66 collapsed, the valve 95 similarly cuts off communication between the pipes 89 and 93 so that if the aperture 37 should be then opened there would be no effect on the bellows 67 or bleed 108. In other words, if the aperture 35 alone is open, the two crest valves 85 and 86 are open. If the aperture 36 alone is open, the two crest valves are opened and the smallest bleed is open. If the aperture 37 alone is open, the two crest valves are open and the intermediate bleed is open. If the aperture 38 alone is open, the two crest valves are open and the largest bleed is open. If the apertures 35 and 36 are open at the same time, only the aperture 35 functions, the operation of the aperture 36 being shut off by the valve 85. Likewise if the apertures 36 and 37 are open at the same time only the aperture 36 functions; and if the apertures 37 and 38 are open at the same time only the aperture 37 functions. When all apertures are closed the crest valves are closed and the softest effect is produced. Aperture 35 opens the crest valves and gives the loudest effect. Aperture 36 opens the crest valves and opens the smallest bleed and gives the next to the loudest effect and likewise the apertures 37 and 38 progressively give softer effects. Otherwise stated, the device may be so set and is here shown so that when all four apertures 35, 36, 37 and 38 are closed, the PP effect is produced. Aperture 35 gives an FF effect. Aperture 36 gives an F effect. Aperture 37 gives a MF effect. Aperture 38 gives a P effect.

There is also apparatus adapted to operate in connection with the rewind. We will now explain this apparatus more in detail. This apparatus comprises primarily the rewind control box E and the bleed shut-off control box F. At the end of each of the pipes 23 where they enter the wind-chest is a shut-off pouch 120. Below the pouch 120 is a chamber 121 into which opens a pipe 122. The pipe 122 leads to the box E (see Figs. 4 and 5). A similar pipe 122^a leads from the box E to the other shut-off pouch (not shown). Within the box E is a valve including the two valve discs 124 and 125 mounted on the valve stem 126. 130

The lower end of the valve stem lies adjacent a diaphragm 127 covering a chamber 128 into which leads a pipe 129. The upper end of the pipe 129 leads to the rewind control in connection with which there is a valve (not shown) adapted to open the end of the pipe 129 to the atmosphere when the rewind is operating and close it during the normal playing operation of the piano. It will be seen that when the valve discs 124, 125 are in the position shown in Fig. 4, the pipes 122 and 122^a connect with the vacuum chamber 45 so that the shut-off pouch 120 is held downwardly as shown in Fig. 2 to keep the end of the pipe 23 open. During the rewind, however, atmospheric air is admitted to the pipe 129. This raises the diaphragm 127 and raises the valve disc 125 to close communication between the pipe 122 and the chamber 45 and also raises the valve disc 124 to open the pipe 122 to the atmosphere. Atmospheric pressure is accordingly admitted into the chamber 121 below the pouch 120 with the result that this pouch is sucked upwardly to close the end of the pipe 23.

Leading from the space in the box E between the valve discs is another pipe 130 similar to the pipe 122 and 122^a. The pipe 130 leads to the box F (see Fig. 4), entering the chamber 131 therein. Below the chamber 131 is a diaphragm 132 covering a chamber 133 into which enters a pipe 134. The pipe 134 leads to the bleed control box C, having its end beside the ends of the pipes 57^a and 59^a. The end of the pipe 134 is likewise adapted to be closed normally by the block 79. When any of the bellows 65, 66, 67 or 68 is collapsed, however, the block 79 is adapted to be raised to open the end of the pipe 134 to the atmosphere. Arranged above the diaphragm 132 is a valve stem 137 provided with the two valve discs 138 and 139 lying in the compartment 140. Leading from the compartment 140 is a pipe 141 which goes to a Y 142 having one branch 141^a leading to the block 60 and another branch 141^b leading to a chamber 150 above the end of the pipe 25 and covered by a diaphragm or pouch 151. In normal operation, the pouch 151 is raised as shown in Fig. 8 to keep the end of the pipe 25 uncovered; but when atmospheric air is admitted through the pipe 141^b, the pouch 151 drops to cover the end of the pipe 25 to shut off all the bleeds. The end of the pipe 141^a leading to the block 60 is normally closed. When, however, it is desired to permanently throw the bleeds out of action, this end is opened by the switch 61 with the result that the end of the pipe 25 is closed. In normal operation, however, the end of the pipe 141^a is closed but atmospheric air is adapted to be admitted into the pipe 141^b from the box F during the rewinding process. This op-

eration is as follows. When the rewind is not operating the valve in box E keeps communication between the pipe 130 and the vacuum chamber 45. Consequently, whenever the end of the pipe 134 is opened to the atmosphere by the operation of any of the bellows in the bleed control box, the valve discs 138 and 139 in the box F are raised so that suction is transmitted from the chamber 131 to the pipe 141 and 141^b to hold up the pouch 151. If, however, the rewind is operating, then there is atmospheric air in the chamber 131 so that whenever any of the bellows in the bleed control box operates, atmospheric air is admitted into the chamber 150 to lower the pouch 151 to shut off the end of the pipe 25.

While we have shown and described certain embodiments of our invention, it is to be understood that it is capable of many modifications. Changes, therefore, in the construction and arrangement may be made without departing from the spirit and scope of the invention as disclosed in the appended claims, in which it is our intention to claim all novelty inherent in our invention as broadly as possible in view of the prior art.

The pipe 216 (see Fig. 6) leads to the rewind motor forming no part of the present invention.

What we claim as new, and desire to secure by Letters Patent, is:

1. In a device of the character described; a perforated music sheet; a tracker-board having apertures controlled by the perforations in the music sheet; a striker-pneumatic; a stack communicating with the striker-pneumatic; a wind-chest; communication between the wind-chest and the stack; a crest valve in the communication between the wind-chest and the stack; a plurality of bleeds; an air connection between each bleed and the wind-chest whereby atmospheric air may be bled into the wind-chest through said bleed; a bleed valve in each of the connections between the bleeds and the wind-chest; means operated by the perforations in the music sheet for opening the crest valve and opening the bleeds.

2. In a device of the character described; a perforated music sheet; a stack; a striker-pneumatic communicating with the stack; a wind-chest adapted to maintain a partial vacuum in the stack; and means for controlling the degree of vacuum in the stack, said means including a crest valve between the wind-chest and the stack controlled by the perforations in the music sheet, and a plurality of bleeds adapted to bleed air through the same and into the wind-chest, said bleeds being provided with valves controlled by the perforations in the music sheet.

3. In a device of the character described;

from the stack; and means for controlling the degree of vacuum in the stack, said means including a passage between the wind-chest and the stack controlled by a 5 crest valve, a plurality of bleeds of different sizes, there being an expression aperture for each bleed, an air connection between each bleed and the wind-chest whereby atmospheric air may be bled into the 10 wind-chest through said bleed, a bleed valve in each of the connections between the bleeds and the wind-chest, and means whereby the uncovering of any of the expression apertures in the tracker-board operates to open 15 the crest valve and the uncovering of certain of such apertures operates to open the smallest of the corresponding bleed valves and prevent the opening of the next larger size bleed valve.

20 10. In a device of the character described; a perforated music sheet provided with a plurality of expression perforations adapted to co-operate with expression apertures in the tracker-board; a striker-pneumatic; 25 a stack communicating with the striker-pneumatic; a wind-chest for exhausting air from the stack; and means for controlling the degree of vacuum in the stack, said means including a passage between the 30 wind-chest and the stack controlled by a crest valve, a plurality of bleeds of different sizes, there being an expression aperture for each bleed, an air connection between each bleed and the wind-chest whereby atmospheric air may be bled into the wind-chest through said bleed, a bleed valve in each of the connections between the bleeds and the wind chest, and means whereby the uncovering of any one of the expression 35 apertures in the tracker-board, operates to open the crest valve, open the corresponding bleed valve, and prevent the opening of the next larger size bleed valve.

the next larger size.

11. In a device of the character described; a perforated music sheet provided with expression perforations; a tracker-board provided with expression apertures adapted to register with the expression perforations in the music sheet; a striker-pneumatic; a stack communicating with the striker-pneumatic; a wind-chest adapted to exhaust air from the stack; and means for varying the degree of vacuum in the stack, said means including a plurality of different size bleeds, there being an expression aperture for each bleed, an air connection between each bleed and the wind-chest whereby atmospheric air may be bled into the wind-chest through said bleed, a valve controlling the connection between each of the bleeds and the wind-chest, said valves controlled by a bleed control box operated by the passage of the expression perforations in the music sheet over the expression apertures in the tracker-board, and means

in said bleed control box whereby the opening of any one of the bleeds prevents the opening of the bleed of the next larger size.

12. In a device of the character described; a perforated music sheet provided with expression perforations; a tracker-board provided with expression apertures adapted to register with the expression perforations in the music sheet; a striker-pneumatic; a stack communicating with the striker-pneumatic; a wind-chest adapted to exhaust air from the stack; and means for varying the degree of vacuum in the stack, said means including a plurality of different size bleeds, adapted to bleed air therethrough into the wind-chest, there being an expression aperture for each bleed, and means whereby the uncovering of any expression aperture opens the corresponding bleed and prevents the opening of the next larger size bleed. 70 75 80 85 90

13. In a device of the character described; a perforated music sheet provided with expression perforations; a tracker-board provided with expression apertures adapted to register with the expression perforations in the music sheet; a striker-pneumatic; a stack communicating with the striker-pneumatic; a wind-chest adapted to exhaust air from the stack; and means for varying the degree of vacuum in the stack, said means including a plurality of different size bleeds, there being an expression aperture for each bleed, an air connection between each bleed and the wind-chest whereby atmospheric air may be bled into the wind-chest through said bleed, a valve controlling each of the connections between a bleed and the wind-chest, and a valve operated by the uncovering of an expression aperture for opening the valve in the communication between the corresponding bleed and the wind-chest.

14. In a device of the character described; a perforated music sheet provided with expression perforations; a tracker-board provided with expression apertures adapted to register with the expression perforations in the music sheet; a striker-pneumatic; a stack communicating with the striker-pneumatic; a wind-chest adapted to exhaust air from the stack; and means for varying the degree of vacuum in the stack, said means including a plurality of different size bleeds, an air connection between each bleed and the wind-chest whereby atmospheric air may be bled into the wind-chest through said bleed, a valve controlling each connection between a bleed and the wind-chest, and a valve controlled by the uncovering of an expression aperture for operating each of the valves in the communications between the bleeds and the wind-chest. 110 115 120 125

15. In a device of the character described; a perforated music sheet provided

- with expression perforations; a tracker-board provided with expression apertures adapted to register with the expression perforations in the music sheet; a striker-pneumatic; a stack communicating with the striker-pneumatic; a wind-chest adapted to exhaust air from the stack; and means for varying the degree of vacuum in the stack, said means including a plurality of different size bleeds, an air connection between each bleed and the wind-chest whereby atmospheric air may be bled into the wind-chest through said bleed, a valve in each of the connections between a bleed and the wind-chest, a valve controlled by the uncovering of an expression aperture for operating each of the valves in the communications between the bleeds and the wind-chest, and an interlocking valve controlled by the uncovering of an expression aperture to prevent the opening of the next larger bleed than the one controlled by that expression aperture.
16. In a device of the character described; a perforated music sheet provided with expression perforations; a tracker-board provided with expression apertures adapted to register with the expression perforations in the music sheet; a striker-pneumatic; a stack communicating with the striker-pneumatic; a wind-chest adapted to exhaust air from the stack; and means for varying the degree of vacuum in the stack, said means including a plurality of different size bleeds, there being an expression aperture for each bleed, an air connection between each bleed and the wind-chest whereby atmospheric air may be bled into the wind-chest through said bleed, valves controlling said connections, a valve for each bleed operated by the uncovering of a corresponding expression aperture and controlling the valve in the communication between the bleed and the wind-chest, and an interlocking valve operated by the uncovering of an expression aperture to prevent the operation of the valve controlling the next larger bleed.
17. In a device of the character described; a perforated music sheet provided with expression perforations; a tracker-board provided with expression apertures adapted to register with the expression perforations in the music sheet; a striker-pneumatic; a stack communicating with the striker-pneumatic; a wind-chest adapted to exhaust air from the stack; and means for varying the degree of vacuum in the stack, said means including a plurality of different size valve-controlled bleeds adapted to bleed air therethrough into the wind-chest, there being an expression aperture for each bleed, and means whereby the uncovering of an expression aperture opens the corresponding bleed.
18. In a device of the character described; a perforated music sheet provided with expression perforations; a tracker-board pro-
- vided with expression apertures adapted to register with the expression perforations in the music sheet; a striker-pneumatic; a stack communicating with the striker-pneumatic; a wind-chest-exhausting mechanism adapted to exhaust air from the stack; and means for varying the degree of vacuum in the stack, said means including a plurality of different size valve-controlled bleeds adapted to bleed air therethrough into the wind-chest, there being an expression aperture for each bleed, and means whereby the uncovering of an expression aperture opens the corresponding bleed and prevents the opening of the next larger size bleed.
19. In a device of the character described; a perforated music sheet provided with expression perforations; a tracker-board provided with expression apertures adapted to register with the expression perforations in the music sheet; a striker-pneumatic; a stack communicating with the striker-pneumatic; a wind-chest adapted to exhaust air from the stack; a passage between the wind-chest and the stack; a bellows arranged adjacent said passage whereby the degree of collapse of said bellows will vary the size of said passage and means operated by the uncovering of any of the expression apertures for contracting said bellows to open said passage.
20. In a device of the character described; a perforated music sheet provided with expression perforations; a tracker-board provided with expression apertures adapted to register with the expression perforations in the music sheet; a striker-pneumatic; a stack communicating with the striker-pneumatic; a wind-chest adapted to exhaust air from the stack; a plurality of bleeds of different size, there being an expression aperture for each bleed; an air connection between each bleed and wind-chest whereby atmospheric air may be bled into the wind-chest through said bleed; a pouch valve for each of the bleeds operable by atmospheric pressure to close the connection between the bleed and the wind-chest; and a valve controlled communication between each pouch valve and the wind-chest, the valves controlling said communications being operated by the uncovering of the expression apertures whereby the uncovering of an aperture operates to open communication between the corresponding pouch valve and the wind-chest to open said pouch valve.
21. In a device of the character described; a perforated music sheet provided with expression perforations; a tracker-board provided with expression apertures adapted to register with the expression perforations in the music sheet; a striker-pneumatic; a stack communicating with the striker-pneumatic; a wind-chest adapted to exhaust air from the stack; a plurality of bleeds of different size, there being an expression aperture for each

bleed; an air connection between each bleed and the wind-chest whereby atmospheric air may be bled into the wind-chest through said bleed; a pouch valve for each of the 5 bleeds operable by atmospheric pressure to close the connection between the bleed and the wind-chest; and a valve controlled communication between each pouch valve and the wind-chest, the valves controlling said 10 communications being operated by the uncovering of the expression apertures whereby the uncovering of an aperture operates to open communication between the corre-

sponding pouch valve and the wind-chest to open said pouch valve; and an interlocking 15 valve controlled by each expression aperture to prevent the operation of the valve controlling the passage between the pouch valve for the next larger size bleed and the wind-chest.

In witness whereof, we have hereunto set our hands and seals this 4th day of January, 1924.

STILLWELL R. HARCOURT. [L. S.]
OSCAR H. ANDERSON. [L. S.]
